UNITED STATES PATENT OFFICE.

PHILIP J. MITTEN, OF PHILADELPHIA, PENNSYLVANIA, ASSIGNOR TO MITTEN-
TRAYLOR INCORPORATED, A CORPORATION OF DELAWARE.

ONE-MAN GASOLINE SAFETY RAIL CAR.

Application filed January 18, 1923. Serial No. 613,393.

To all whom it may concern:

Be it known that I, PHILIP J. MITTEN, a citizen of the United States, residing at Philadelphia, county of Philadelphia, State 5 of Pennsylvania, have invented a new and useful One-Man Gasoline Safety Rail Car, of which the following is a specification.

There are large numbers of standard or conventional trolley lines or extensions 10 thereof, which owing to adverse business conditions, the cost of maintenance of power plant, poles, overhead trolley wires and their adjuncts and their extensions through sparsely populated territory, which has not 15 been built up according to expectations, cannot be operated except at a loss, and are at the present time being discontinued or going into bankruptcy, notwithstanding the power plant and rails or trackway are in 20 good condition. There is under existing conditions a demand for a limited or restricted amount of transportation service and yet not enough to warrant the maintenance and upkeep of the power plant, wire 25 and poles aforesaid.

The object of my present invention is to provide a novel railway car construction, wherein each car is a novel construction of a one-man car and equipped with its own internal combustion engine, which is located 30 in the front of the car below the floor thereof, and in such a position that the single operator is brought as near to the front of the car as possible, so that he stands or sits 35 directly over the engine below the car floor so as to provide a maximum seating capacity, said engine being preferably of the horizontal type or having horizontally disposed cylinders cooled by a horizontally positioned cooling coil in contradistinction to the vertical front radiator commonly employed, said cooling coil being also located 40 below said car floor. An upright engine may also be used at either end of the car and the engine irrespective of its type can be located at the front, rear or center of the car or the control means at both ends.

By the employment of a horizontal gas engine having its cylinders disposed horizontally, I am enabled to position the engine shaft at the desired point below the car floor, so that a direct connection can be made to the propellor shaft and its adjuncts, from which power is transmitted simulta-

neously to both the car axles. I have found 55 it desirable or essential from an engineering standpoint in a railway car of the character I employ, for the axles to be approximately seven feet six inches to eight feet apart or more and to be provided at their juxtaposed inner ends, which are located at the longitudinal median line or any other line of the car, with or without differentials, which permit the car wheels to follow the curvatures of the track. A transmission 60 and gear shift is employed under the control of the motorman, having the necessary change of speeds forward and reverse; it being further understood that power is taken in any suitable manner from the propellor shaft to both the front and rear 65 axles, so that a direct drive or traction to the desired extent is simultaneously exerted 70 upon both the front and rear wheels.

My invention comprehends a novel motor vehicle using standard automobile parts with flanged wheels on the axles thus eliminating the use of trolley car, truck wheels, truck springs etc., making a more flexible drive and giving more comfortable riding 80 qualities. This combination can be run and maintained for a lower cost per mile than the expense of a centrally located electric power plant alone, and therefore a company, which is insolvent, using electrically driven 85 trolleys, can sell their electric equipment and cars, and with the money so obtained buy a sufficient number of my gas engine driven vehicles and place the system on an immediately profitable basis.

My invention further comprehends a novel one-man street railway car of the character described having the driving mechanism located below the floor level of the car.

My invention further consists of other novel features of advantage and construction, all as will be hereinafter set forth and pointed out in the claims.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not lim-

ited to the precise arrangement and organization of these instrumentalities as herein shown and described.

Figure 1 represents, in side elevation, a 5 one-man gasoline safety rail car, embodying my invention.

Figure 2 represents a section on line 2—2 of Figure 1.

Figure 3 represents a sectional plan view 10 of another embodiment of my invention.

Figure 4 represents a top plan view of the chassis.

Figure 5 represents a section on line 5—5 of Figure 4.

Similar numerals of reference indicate 15 corresponding parts.

Referring to the drawings,

1 designates a one-man gasoline safety rail car, embodying my invention, which is 20 provided with a car body 2 and a chassis 3. The chassis 3 is preferably made up of structural metal beams and, as illustrated, an internal combustion engine 4 is carried by the supporting brackets 5 secured to the 25 chassis. This internal combustion engine may be located at any desired point in the length of the chassis but, as illustrated in Figures 4 and 5, it is located at the forward end of the vehicle so that it will be carried 30 below the floor line 6 of such vehicle. The cylinders of the engine are preferably disposed laterally instead of vertically. The engine is provided with a cooling system which includes a radiator 7 which is preferably laterally instead of vertically disposed and is located below the floor line of the vehicle. The engine shaft 8 is provided with a fly wheel 9, and is connected with a connecting rod 10 which extends to the 35 transmission gear box 11, and is intergeared in any desired manner with the forward driving shaft 12 and the rear driving shaft 13. The gear box is suspended from the channel frame of the chassis by means of 40 the brackets 14. The shaft 12 is intergeared with the differential 15 operatively connected with the front axle 16 which carries the front flanged wheels 17 in order that such 45 wheels may run on the track 18. The rear shaft 13 is connected with the rear differential 19 which is operatively connected with the rear axle 20 which carries the rear flanged driving wheels 21, it being understood that all four wheels act as driving 50 wheels. The front housing 22 carries the front springs 23 connected with the brackets 24 secured to the frame of the chassis. In a similar manner the rear housing 25 is secured to the rear springs 26 which are 55 connected with the brackets 27 secured to the chassis frame.

It will thus be understood that all of the driving mechanism, including the internal combustion engine and its cooling means is 60 located beneath the floor line 6, so that the

entire space above the floor line is available for transportation purposes.

In the embodiments seen in Figures 1, 2, 4 and 5, the car is illustrated as being of the one-man type, the operator being at the 70 forward end of the car, and in rear of such operator, a vestibule 28 is provided in close proximity to its forward end, the door openings 29 being controlled by the foldable doors 30 which fold into the vestibule. The vestibule is provided with a depressed portion 31 extending below the floor line so that the step portion 32, see Figure 1, will be readily accessible for the passengers.

In this embodiment of my invention, the 80 seating arrangement is shown at 33, from which it will be understood that a maximum carrying capacity is provided. The arrangement is such that a seating capacity 85 is provided for twenty-one people.

In the embodiment seen in Figure 3, the construction and arrangement of the driving mechanism is the same as that already described, but I have shown the opposite 90 ends of the car as adapted to receive the station for the one man operator, and a foldable seat 33' is provided, which, together with the side seats 34, will adapt the car to seat twenty-six passengers. In this arrangement instead of having two doors at 95 the same end of the car, one door arrangement 35 similar to that already described in connection with Figure 2 is at the right-hand forward end of the car, and when the car is to travel in an opposite direction, the 100 entrance 36 is employed, at which time the one man operator of the car is stationed at such end of the car. In this manner, I provide for the car being operated by the operator in either direction without rendering 105 it necessary to turn the car around in order to drive it in the opposite direction. In this case the window at the front of the car and the arrangement of the body at each 110 end will be the same, while in the embodiment seen in Figure 2, the front end of the car will be adapted for the use of the one man operator, and the rear end of the car can have any conventional form of construction.

It will be apparent from the foregoing that in accordance with my present invention, a railway car which dispenses with steering mechanism can be operated on 115 tracks at a minimum cost of operating expense, since the power plant is built into the car and the trolley poles and feed lines and other necessary equipment for ordinary trolley railway traffic lines is dispensed with.

I am also enabled to economically construct and operate the driving mechanism, since an internal combustion engine is employed, and standard automobile parts may be used for the driving mechanism and its adjuncts. By disposing the driving mech-

anism in the manner herein set forth, the maximum seating or carrying capacity of the car body is obtained without any interference with the operator in carrying out his 5 duties of operating the car from either end, controlling the car doors and collecting fares by the controlling means 37 located in the vestibule 28.

My novel construction of driving mechanism or power transmission devices positioned below the car floor is differentiated 10 from a four wheel truck or automobile device, for the reason that the axles are each provided with a flanged solid car wheel fixedly secured thereto which travels on rails and both sets of axles or wheels entirely dispense with and are entirely disassociated from any steering mechanism, knuckles, elbow levers or transverse rods of the character employed in trucks or other self propelled vehicles of the conventional character, since the flanged car wheels obviously 20 follow the curvatures of the rails without requiring attention on the part of the motorman or operator. While I preferably employ a horizontally disposed gasoline motor or one having its cylinders extending horizontally together with a horizontally disposed cooling system in order that the source 25 of power and all the transmission or driving mechanism may be entirely below the floor line, so as to bring the motorman as far forward as possible to provide a maximum seating capacity, it will be evident that 30 a vertical engine, if properly designed and positioned, might be employed and the radiator or cooling system may be arranged differently from the position seen provided it is carried sufficiently forward or is disposed as to be out of the way of the motorman and occupants or passengers of the car. I have deemed it unnecessary to describe in 35 detail the construction of the differentials, transmission, forward and reverse gear shifts or controls located in the car vestibule, universal joints, engine or door actuating mechanism, as standard units of any desired design may be employed, provided that the drive is connected to all the axles and the outer end of each axle has fixedly secured thereto a flanged drive wheel adapted to follow the treads of the rails and that all of said axles and wheels are disassociated with any steering mechanism.

It will be obvious from the foregoing that I have provided a one-man safety gasoline driven car having its motive power and driving mechanism so disposed below the floor as to give uninterrupted floor space to accommodate the maximum number of passengers possible in the limited floor space present in this type of car.

It will now be apparent that I have devised a novel and useful one-man gasoline safety rail car, which embodies the features

of advantage enumerated as desirable in the statement of the invention and the above description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what I claim as new and desire to secure by Letters Patent is:

1. A railway car comprising a body frame, 80 a body, a motor supported by said frame beneath the forward end of said body, front and rear axles including wheels yieldably supporting the body frame, a transmission supported by said frame intermediate of said axles, means operatively connecting said motor with said transmission, and drive means independently connecting said transmission with each axle.

2. A railway car comprising a body frame, 90 a body, a motor supported by said frame beneath the forward end of said body, front and rear axles including wheels yieldably supporting the body frame, a transmission supported by said frame intermediate of 95 said axles, flexible means operatively connecting said motor with said transmission, and drive means independently connecting said transmission with each axle.

3. A railway car comprising a body frame, 100 a body, a motor supported by said frame beneath the forward end of said body, front and rear axles including wheels yieldably supporting the body frame, a transmission supported by said frame intermediate of 105 said axles, means operatively connecting said motor with said transmission, and flexible drive means independently connecting said transmission with each axle.

4. A railway car comprising a body frame, 110 a body, a motor supported by said frame beneath the forward end of said body, front and rear axles including wheels yieldably supporting the body frame, a transmission supported by said frame intermediate of 115 said axles, means operatively connecting said motor with said transmission, and means connecting said transmission with each axle.

5. A railway car comprising a body frame, 120 a body, a motor supported by said frame beneath the forward end of said body, front and rear axles including wheels yieldably supporting the body frame, a transmission supported by said frame intermediate of 125 said axles, a propeller shaft including complementary universal joints connecting said motor with said transmission and drive means independently connecting said transmission with each axle.

6. A railway car comprising a body 130

frame, a body, a motor supported by said frame beneath the forward end of said body, front and rear axles including wheels yieldably supporting the body frame, a transmission supported by said frame intermediate of said axles, means operatively connecting said motor with said transmission, drive means positively connecting said transmission with the front and rear axles whereby propulsion of at least one axle ¹⁰ takes place, should one of said drive means cease to function.

PHILIP J. MITTEN.
